Dallas, Tex. 75214

Filed Apr. 3, 1967, Ser. No. 6,487

Term of patent 14 years

(Cl. D97—1)

Fig.1

Fig.2

FIGURE 1 is a perspective view showing the front panel and backbone of a loose-leaf notebook cover of my new design;

FIGURE 2 is a plan view of the inside of the notebook cover at a fully opened position.

The back panel of the notebook cover opposite that shown in FIGURE 1 is plain.

The essential features of the design reside in the portions shown in solid lines, a conventional binder strip and rings being shown in broken lines.

I claim:

The ornamental design for a loose-leaf notebook cover, substantially as shown and described.
